Des. 1719

Joseph A. Bailly of Philadelphia Penn,
Letters Patent No 1719. Dated Feby 3. 1868.

The schedule referred to in these Letters Patent and making part of the same.

To all whom it may concern:

Be it known that Joseph A. Bailly of Philadelphia, State of Pennsylvania have invented or produced a new and original design for a statuette; and I do declare the following to be a full and exact description of the same.

The design consists of an equestrian statuette of General McClellan and may be made in Plaster, clay, marble, bronze or other suitable material, The annexed photograph shows fully the design.

What I claim as my invention is the design for a statuette shown in the annexed photograph.
